EAR CAP FOR AUDITORY PROTECTION

Bo Gunnar Lonnstedt, Kvarnbergsvagen 23,
S-141 45 Huddinge, Sweden

Filed Apr. 16, 1974, Ser. No. 461,422

Claims priority, application Sweden Oct. 16, 1973

Term of patent 14 years

Int. Cl. D2—03

U.S. Cl. D2—259

FIG. 1

FIG. 2

FIG. 3

FIG. 4

FIG. 5

FIG. 1 is a perspective view of the outer side of an ear cap for auditory protection showing my new design;

FIG. 2 is a side elevational view thereof;

FIG. 3 is a perspective view from the underside thereof;

FIG. 4 is a perspective view of the outer side thereof, from the side opposite FIG. 1; and

FIG. 5 is a perspective view from the underside thereof but from the side opposite FIG. 3.

I claim:

The ornamental design for an ear cap for auditory protection, as shown.
